UNITED STATES PATENT OFFICE.

CHARLES L. SCHUTZE, OF HANNIBAL, MISSOURI.

MUSICAL CHART.

1,214,380.

Specification of Letters Patent. Patented Jan. 30, 1917.

Application filed June 6, 1916. Serial No. 101,998.

To all whom it may concern:

Be it known that I, CHARLES L. SCHUTZE, a citizen of the United States, residing at Hannibal, in the county of Marion and 5 State of Missouri, have invented new and useful Improvements in Musical Charts, of which the following is a specification.

This invention relates to musical charts and has particular application to a musical 10 key indicator.

The chief characteristic of this invention resides in the provision of a device of this character having a dial and a finder, the dial having musical indicia thereupon while 15 the finder is provided with openings for exposing some of the indicia whereby any desired scale in music and the relative minor scale may be easily and automatically determined, together with the signature.

20 Other objects of the invention will appear as the specification is read in connection with the accompanying drawings in which:—

Figure 1 is a plan view of the device 25 constructed in accordance with my invention. Fig. 2 is a vertical central section of Fig. 1.

Referring to the drawings in detail, my 30 invention comprises a sheet 1 formed of any suitable material such as cardboard or the like, and which in this instance is of rectangular formation. Extending transversely through the sheet 1 at a point centrally thereof is a stud 2 upon which is pivotally 35 mounted a finder strip 3, the latter being elongated and pivotally connected to the stud at its medial portion. Inscribed upon the sheet 1 and arranged concentrically of the stud 2 is a spaced circular series of 40 numerals 4 which range from 0 to 7 to indicate the number of sharps or flats in the respective keys as will be hereinafter described. Arranged concentrically of the numerals 4 and in spaced relation thereto 45 is a circular series of letters 5 ranging from A to G inclusive which are adapted to indicate the major keys in sharps. The next series of letters as indicated as at 6 designate the major keys in flats while the two 50 outer series 7 and 8 respectively indicate the relative minor keys in sharps and flats respectively.

It will be noted that all of the numerals and letters within each of the series are 55 arranged in radial alinement with each

other as is clearly shown in Fig. 1 of the drawings.

The finder strip 3 has its medial portion, or that portion adjacent its pivot, widened as at 9 in such a manner as to overlie and thus conceal the series of numerals 4. The opposite ends of the finder strip or those portions which are disposed upon opposite sides of the pivot are provided with a longitudinally extending series of spaced openings 10 and 10' which are preferably circular in contour. The openings 10 are designed to expose the major scale, while the openings 10' will expose the relative minor scale. The series of openings upon one side of the 70 pivot are designed and so disposed as to reveal the major and relative minor keys in flats and the corresponding number of flats, while the openings upon the opposite end expose the major and relative minor keys 75 in sharps and the corresponding number of sharps. From this it will be seen that the openings upon the flat indicating side are disposed so as to reveal certain of the numbers in the inner series 4 and certain of the 80 letters in each of the series 6 and 8, while the openings upon the opposite end reveal certain of the numerals in the inner series 85 and certain of the letters in each of the series 5 and 7.

It will thus be seen that I have provided three openings upon each side of the pivot, the openings being so arranged as to expose certain of the series of letters as previously described. Inscribed upon the finder strip 90 3 and arranged adjacent the openings 10 are indicia indicating the information divulged by each of the openings, that is to say the two inner openings or those adjacent the pivot are provided with indicia "No." and the sign used to indicate flats and sharps respectively, while the openings adjacent the inner openings in each of the series has the word "Major" inscribed adjacent thereto, and the outer openings in each of the series are provided with the indicia "Minor" and the character sharp and flat respectively.

It will be seen from this construction 105 that when the finder strip is rotated upon the sheet to the desired key, the openings will reveal the key note, the relative minor key and the number of flats or sharps in the key so that the operator may quickly 110 ascertain this information. The indicia in-

scribed upon the sheet contain all of the major keys in sharps and flats, the natural key, and the relative minor keys, so that it will be seen that I have provided means for 5 ascertaining the relative minor key and corresponding number of sharps and flats in any of the keys.

It is thought from the foregoing taken in connection with the accompanying drawings 10 that the construction and operation of my device will be apparent to those skilled in the art without further description, and that minor changes in size, shape, proportion and various arrangements of the key signatures 15 may be made without departing from the spirit and scope of the appended claims.

What I claim.

1. A musical chart comprising a sheet 20 having key notes inscribed thereon and arranged in concentrically disposed circles indicative, respectively, of the major keys in sharps, the major keys in flats, the relative minor keys in sharps and the relative minor keys in flats, and a finder strip pivoted between its ends at the center of said symbols and having the end portions thereof formed with openings corresponding with the series of notes respectively.

2. A musical chart comprising a sheet 30 having inscribed thereon a circular series of numerals indicating the number of sharps or flats in each key and arranged in concentric relation to the center of the sheet, key notes arranged in concentrically disposed circles about the first mentioned series, the key notes of each series being in radial alinement with the numerals in the first mentioned series, and a finder strip pivoted between its ends at the center of the first mentioned series and having the end portions thereof formed with openings, the openings

in one end portion of the strip registering with certain of the respective series and the openings in the other end portion of the strip registering with certain of the other 45 series.

3. A musical chart comprising a sheet having inscribed thereon a circular series of numerals indicating the number of sharps or flats in each key and arranged in concentric relation to the center of the sheet, key notes arranged in concentrically disposed circles about the first mentioned series, and a finder strip pivoted between its ends at the center of the first mentioned series and 50 having the end portions thereof formed with openings, the openings in one end portion of the strip registering with certain of the respective series and the openings in the other end portion of the strip registering 55 with the remaining series.

4. A musical chart comprising a sheet having inscribed thereon a circular series of numerals, key notes arranged in concentrically disposed circles about the numerals, the 60 key notes in the respective circles being in radial alinement with the numerals, a finder strip pivoted between its ends at the center of said numerals and having the end portions thereof formed with a longitudinally 65 extending series of openings, the series on one end being arranged to expose the major and relative minor keys in flats and the corresponding number of flats while the openings upon the opposite end are adapted to 70 expose the key notes in sharps and the corresponding number of sharps, and indicia inscribed upon the finder strip adjacent each of said openings for indicating the information disclosed in the openings.

In testimony whereof I affix my signature.
CHARLES L. SCHUTZE.
